F. EVANS.

MILK BOTTLE HOLDER,
APPLICATION FILED MAR. 7, 1918.

1,324,444.

Patented Dec. 9, 1919.

Inventor
Fred Evans
By his Attorney

Charles H. Wilson

UNITED STATES PATENT OFFICE.

FRED EVANS, OF SUMMIT, NEW JERSEY, ASSIGNOR TO L. EUGENE FIELD, OF BROOKLYN,
NEW YORK.

MILK-BOTTLE HOLDER.

1,324,444.

Specification of Letters Patent.

Patented Dec. 9, 1919.

Application filed March 7, 1918. Serial No. 220,892.

To all whom it may concern:

Be it known that I, FRED EVANS, residing at Summit, in the county of Union and State of New Jersey, have invented certain new and useful Improvements in Milk-Bottle Holders, of which the following is a specification.

This invention relates to a new and improved milk bottle holder, and one of the 10 objects thereof is to provide a holder of the class described adapted for locking one or more bottles therein, irrespective of the height of the bottles.

Another object is to provide a device of 15 this character of simple construction and which may be manufactured at a modicum of cost.

Other objects will be in part obvious and in part pointed out in the course of the following description.

In the accompanying drawings, wherein I have illustrated a preferred embodiment of my invention:

Figure 1 is a side elevational view thereof, showing the device adapted for supporting two milk bottles.

Fig. 2 is a top plan view, partly in section.

Fig. 3 is a fragmentary view showing a 20 slightly different embodiment of my invention; and

Fig. 4 is a top plan view, partly in section, of the embodiment shown in Fig. 3.

Referring now to the drawings, wherein 25 the similar reference characters refer to similar parts, the reference numeral 1 indicates the base member of the device, which consists of a plate provided upon its periphery with a plurality of upstanding members 2, which with the base 1 provide a socket adapted to receive a bottle 3. Suitably fixed in a socket provided to one side of the base member 1 is an upright post 4 and slidably mounted upon this post is a

40 bracket 5, comprising the plate 6 and the peripherally disposed uprights 7. This plate 6 is also provided with a depending cup-shaped member 8 adapted to receive and engage the upper end of the milk bottle 3. Slidably mounted upon the post 4 above the bracket 5 is a second bracket 9. This bracket consists of a plate 10 having a part thereof bent to encircle three sides of the post 4, as shown in Fig. 2, leaving the

55 front face of the post exposed. The plate

10 is also provided with an inwardly extending lug 11 to which is secured a cup 12, as by the rivet 13. The cup 12 is shaped similarly to the cup-shaped member 8, and is adapted to receive and engage the upper 60 end of a second bottle indicated at 14. Swiveled at 15 upon the plate 10 is a lever 16, provided with an opening 17, which when the parts are in the position shown in Figs. 1 and 2, lies in registry with an opening 18 in the plate 10. The inner end of the lever 16 is provided with a longitudinal slot adapted to receive a pin 19 provided upon a locking member 20 which is also swiveled, as at 21, upon the plate 10. The 70 inner end of the locking member 20 is provided with an enlarged portion 22 which is adapted to engage the post 4 when the parts are in the position shown in Figs. 1 and 2 of the drawings, and this enlarged portion 22 may be provided with teeth, as at 23, if desired.

Locking member 20 is swiveled upon the plate 10 at a point which is at a less distance from the post than the distance between the pivot 21 to the inner end of the lever, whereby when the parts are in the position shown the end 22 is held forcefully in engagement with the surface of the post 4, by means of the lever 16. This wedging action operates to lock the bracket 9 to the post 4 at any position in which it may be desired to lock the same. When the parts are in the position shown with the openings 17 and 18 in registry, the locking member 24 of a lock 25 may be inserted in said openings, thereby locking the lever 16 to the plate 20 and holding the locking parts in the position shown in Figs. 1 and 2 of the drawings. A stop, as at 26, may be provided upon the post 4, whereby the parts which are slidably mounted upon the post 4 are prevented from being removed entirely from said post.

Referring now to Figs. 3 and 4, a slightly 100 different embodiment of the invention is shown in that the bracket 27, which corresponds to bracket 9 of the first described embodiment, is provided with a laterally extending threaded shank 28. This shank 105 28 is provided with an arm 29 shown in the drawings as being an integral part thereof. This arm carries a cup-shaped member, similar to those above described, which is indicated at 30. Threaded into the 110

shank 28 is a screw 31, and fixedly mounted upon the outer end of said screw is an arm 32. Arms 29 and 32 are provided with openings 33 and 34 respectively, which when said arm 32 is swung downwardly will register with each other so that the locking member of a lock may be projected therethrough.

The inner end of the screw 31 is preferably pointed, as at 35, so that the same will engage with the post 4 when the arm 32 is moved into parallel relation with the arm 29.

The thread provided in the shank 28 is what is known as a "quick thread", or in other words, it is a thread of a very high object, so that a slight angular movement between the arm 32 and the arm 29 will give the screw 31 considerable movement within the shank 28. The screw is of such length that when the arms 32 and 29 are in parallel relation it will have such a tight engagement with the post 4 that the bracket 35 will be locked in position upon said post.

Having thus described my invention, the operation thereof may now be understood. As will be obvious from the drawings, a bottle may be inserted upon each of the plates 1 and 6, and the bracket 5 may be lowered so that the cup 8 receives and engages the upper end of the bottle 3, and that the bracket 9 may be lowered so that the cup 12 thereof engages the upper end of the bottle 14. This operation is, of course, effected when the locking device 24 has been removed from the openings 17 and 18 of the lever 16, and the plate 10 and the lever 16 raised to release the locking device.

It will be understood that the person to whom the bottles are to be delivered leaves the device in an unlocked position so that the delivery man can insert the bottles in position and then manipulate the parts so that the bottles are held in position, whereupon he inserts the locking member as above described and snaps the lock. The person having the key can then release the bottles from their locked condition whenever desired.

A similar operation of the parts in Figs. 3 and 4 will lock and unlock the bottles in the device, the inner end of the screw 31 operating to frictionally engage the post 4 and hold the bracket 27 firmly against sliding movement on the said post.

While I have shown the construction as adapted to receive and lock two milk bottles, it will be understood that it may be constructed to similarly operate upon a greater number, and it will also be understood that the device as shown by the drawings can be manipulated to lock a single bottle as well as two. This is accomplished by inserting a bottle in the lower socket and then moving bracket 9 downwardly until the cup 12 en-

gages the upper surface of the plate 6, whereupon the locking device can be manipulated as above described.

It will accordingly be seen that I have provided a device well adapted to attain, among others, the objects above specified, in a simple and efficient manner by reason of the fact that the locking device is frictionally engaged by the upright, and bottles of various height can be securely and firmly locked in position.

As many changes could be made in this construction without departing from the scope of the following claims, it is intended that all matter contained in the above description or shown in the accompanying drawing shall be interpreted as illustrative only and not in a limiting sense.

Having thus described my invention what I claim as new and desire to secure by Letters Patent is:

1. In a device of the class described, in combination, a base member provided with a socket, a post carried by said base member, a bracket, a slidably mounted member upon said post being provided with a socket, said first mentioned socket and said second mentioned socket being adapted to engage respectively the lower and upper ends of a bottle, a second socket carried by said bracket adapted to support a bottle, a second bracket mounted upon said post having a socket adapted to engage the upper end of a second bottle, and means carried by said second bracket adapted frictionally to engage said post to lock said bracket thereto.

2. In a device of the class described, in combination, a base member having a socket, a post carried by said base member, a bracket mounted to slide upon said post, said bracket having a pair of oppositely disposed sockets, a second bracket mounted upon said post having a downwardly disposed socket and means for frictionally locking said second mentioned bracket to said post.

3. In a device of the class described, in combination, a base member provided with a post, a socket provided upon said base member, a slidable bracket mounted on the post provided with a socket, each of said sockets being adapted to support a bottle and a bracket slidably mounted upon said post adapted to engage the uppermost bottle provided with means for frictionally locking the same to the post.

4. In a device of the class described, in combination, an upright post and a plurality of members mounted upon said post, each of which is provided with a socket adapted to support a bottle, and one of said members having a socket adapted to engage the upper end of a bottle, one of said members having means for frictionally locking itself to said post, whereby another of

said members, together with the interposed bottles, are locked in position.

5. In a device of the class described, in combination, a base member having a socket, an upright post carried by said base member, said socket being adapted to support a bottle, a bracket carried by said post having a socket adapted to receive the upper end of a bottle, and a pair of levers mounted upon 10 said bracket, one of which is provided with

means for frictionally engaging said post, and means for locking said levers whereby such frictional engagement is established with the post and the bracket locked thereto.

In testimony whereof I affix my signature 15 in the presence of two witnesses.

FRED EVANS.
